(57) **CLAIM**

The ornamental design for an elf toy, as shown and described.

DESCRIPTION

FIG. 1 is a top perspective view of an elf toy;

FIG. 2 is a front view of the elf toy taken from FIG. 1;

FIG. 3 is a back view of the elf toy of FIG. 1;

FIG. 4 is a left view of the elf toy of FIG. 1.

FIG. 5 is a right view of the elf toy of FIG. 1;

FIG. 6 is a top view of the elf toy of FIG. 1; and,

FIG. 7 is a bottom view of the elf toy of FIG. 1.

The broken lines depicting the doll's hairline in the drawing are for illustrative purposes only and form no part of the claimed design.
